COIN OPERATED TYPEWRITER CONTROL APPARATUS

Jesse E. Graham, San Diego, Calif., assignor of
one-half to Stanley Erl Stensrud, San Diego,
Calif.

Application August 3, 1940, Serial No. 350,451

2 Claims. (Cl. 197—193)

My invention relates to a coin operated typewriter control apparatus, more particularly for use in periodical public rental of typewriters and the objects of my invention are:

First, to provide an apparatus of this class which may be positioned in numerous different public places for use by persons desiring typewriter service whereby said persons may use a typewriter controlled by my apparatus over a given period of time for a coin which may be inserted in a coin receiving device in connection with my apparatus;

Second, to provide an apparatus of this class which is arranged to receive a coin and automatically release the operating keys of the typewriter in connection therewith for a given period of time, then to automatically lock the typewriter keys until another coin is inserted in the coin receiving mechanism;

Third, to provide an apparatus of this class to which a typewriter is securely fastened and arranged to prevent the removal of the same by unauthorized persons;

Fourth, to provide an apparatus of this class in which a timing device controls the latch mechanism in connection with the typewriter and which timing mechanism is set for interval operation by a coin receiving device;

Fifth, to provide an apparatus of this class which is not easily tampered with and which is accurate and efficient in limiting the time operating period of the typewriter in connection therewith;

Sixth, to provide an apparatus of this class which is very compact and easy to operate and install;

Seventh, to provide an apparatus of this class which renders the typewriter in connection therewith inoperative until the service thereof is paid for;

Eighth, to provide an apparatus of this class which is applicable to various types and makes of typewriters; and

Ninth, to provide an apparatus of this class which is very simple and economical of construction, efficient in its action and which will not readily deteriorate or get out of order.

With these and other objects in view as will appear hereinafter, my invention consists of certain novel features of construction, combination and arrangement of parts and portions, as will be hereinafter described in detail and particularly set forth in the appended claims, reference being had to the accompanying draw-

ings and to the characters of reference thereon which form a part of this application in which:

Figure 1 is a fragmentary sectional view of my coin operated typewriter control apparatus taken from the line 1—1 of Fig. 3 showing diagrammatically by dash lines the connection of portions of a conventional typewriter with said apparatus; Fig. 2 is a fragmentary sectional view taken from the line 2—2 of Fig. 1 showing portions broken away to facilitate the illustration; Fig. 3 is a fragmentary sectional view taken from the line 3—3 of Fig. 1 showing diagrammatically the connection of the coin receiving mechanism with my coin operated typewriter control apparatus, also showing by dash lines varying positions of parts of said apparatus and Fig. 4 is an enlarged fragmentary sectional view taken from the line 4—4 of Fig. 3 showing portions in elevation to facilitate the illustration.

Similar characters of reference refer to similar parts and portions throughout the several views of the drawings.

The cabinet 1, cabinet lock 2, mechanism casing 3, timing mechanism 4, ratchet wheel 5, ratchet pawls 6 and 7, operating lever 8, latch arm 9, trip lever 10, typewriter key retaining lever 11, latch member 12, latch member operating lever 13 and the coin receiving mechanism 14 constitute the principal parts and portions of my coin operated typewriter control apparatus.

The cabinet 1 is substantially box-like in construction and is enclosed at its upper side by means of the top member 1a which is hinged at its one side on the hinge 1b, as shown best in Fig. 1 of the drawings and forms a table top for supporting a typewriter thereon.

The cabinet lock 2 is a conventional tumbler lock which is arranged to lock the top member 1a securely in closed position, as shown in Fig. 1 of the drawings. The typewriter, as shown by dash lines in Fig. 1 of the drawings is secured to the top member 1a by means of the bolts 1c, it being noted that the bolts 1c are positioned with their head portions internally of the top member 1a so that the typewriter may not be removed from the top member 1a unless the cabinet 1 is opened. The mechanism casing 3 is positioned inside the cabinet 1 and is arranged to contain and support the principal mechanism of my apparatus.

The timing mechanism 4 is secured on the lower side of the substantially rectangular plate member 1d, as shown best in Figs. 2 and 3 of the

drawings and is in the form of a modified clock works. This timeclock mechanism 4 is a substantially conventional mechanism such as is used in pocket watches. The main spring means of this timeclock mechanism 4 is modified, otherwise this timing mechanism 4 is a partially complete clock works. The main spring casing 4b of this timing mechanism 4, as shown best in Fig. 4 of the drawings is provided with an outwardly extending shaft 4c to which is secured the ratchet wheel 5 by means of a pin 5a. It will be here noted that the conventional main spring of the timing mechanism 4 is removed from the main spring casing 4b, as shown best in Fig. 4 of the drawings. The ratchet pawls 6 and 7 in connection with the operating lever 8 provide rigid engaged relation of the operating lever 8 with the ratchet wheel 5 in connection with the main spring casing 4b. The operating lever 8 is pivotally mounted on the hub portion 5b of the ratchet wheel 5, as shown best in Figs. 3 and 4 of the drawings. Secured to one end of this operating lever 8 is a tension spring 8a which tends to pivot the operating lever 8 on the hub portion 5b of the ratchet wheel 5. The ratchet pawls 6 and 7, in engagement with the ratchet wheel 5, transmit the tension of the spring 8a to the ratchet wheel 5 in connection with the main spring casing 4b providing operating tension on the main spring casing 4b tending to revolve the casing 4b and operate the modified clockworks in the conventional manner by means of the gear teeth 4d at the periphery of the main spring casing 4b. In this manner the tension spring 8a replaces the conventional clockworks main spring which is omitted from the main spring casing 4b, as shown best in Fig. 4 of the drawings. Rigidly secured to the upper side of the operating lever 8 is an upwardly extending pin 8b as shown best in Figs. 2 and 3 of the drawings.

Pivottally mounted on the plate 4a is the latch arm 9, as shown best in Fig. 3 of the drawings. This latch arm 9 is pivotally mounted on the pin 9a at its one end and is provided with a spacer 9b thereon intermediate the plate 4a and the end of the latch arm 9. The tension spring 9c is arranged to force the latch arm 9 inwardly toward the upwardly extending pin 8b of the operating lever 8. The latch arm 9 is provided with a notch portion 9d in its one side arranged to engage a pin 10a extending upwardly from the trip lever 10. The extending end of the latch arm 9 is curved and is arranged to be engaged by the pin 8b of the operating lever 8.

The trip lever 10 is pivotally mounted on the pin 10b secured to and extending upwardly from the plate member 4a, as shown best in Fig. 3 of the drawings. Secured to one end of the trip lever 10 is a tension spring 10c which tends to pivot the trip member 10 on the pin 10b and force it into the dash line position F, as shown in Fig. 3 of the drawings. The typewriter key retaining lever 11 is pivotally mounted on a pin 11a in connection with the bracket 11b secured on the top member 3a of the mechanism casing 3. This top member 3a is provided with a slotted portion 3b therein in which the typewriter key retaining lever 11 is shiftably positioned. Secured to this typewriter key retaining lever 11 is a tension spring 11c which is supported by the pin 11d extending from the under side of the top member 3a, as shown best in Fig. 1 of the drawings.

The latch member 12 is pivotally mounted on a bracket 12a which is secured by means of screws to the bottom portion 3c of the mechanism casing 75

3, as shown best in Figs. 1 and 3 of the drawings. This bracket 12a is provided with an outwardly extending portion 12b in which is positioned the pin 12c, which pin 12c forms the pivotal support for the latch member 12. This latch member 12 is provided with a pair of substantially parallel spaced arm members 12d and 12e, as shown best in Fig. 3 of the drawings. These arm portions 12d and 12e are provided with hook portions 12f and 12g respectively. The hook portions 12f and 12g are arranged to engage the edge portion 11e of the typewriter key retaining lever 11 for limiting its pivotal movement urged by the spring 11c, as shown by dash lines in Figs. 1 and 3 of the drawings. Secured to the arm portion 12e of the latch member 12 is a tension spring 12h. The opposite end of the spring 12h is secured on an outwardly extending portion 12j of the bracket 12a, as shown best in Fig. 3 of the drawings. The angularly extending portion 12k of the bracket 12a is arranged to limit the pivotal movement of the typewriter key retaining lever 11 urged by the spring 11c and to hold the same in the solid line position, as shown best in Figs. 1 and 3 of the drawings. The latch member 12 is also provided with downwardly and outwardly extending portions 12m in which is positioned a pin 12n. This pin 12n is positioned in the slotted portion 13a of the latch member operating lever 13. This latch member operating lever 13 is pivotally mounted on the pin 13b secured to the bracket 13c, which bracket 13c is positioned on the inner side of the mechanism casing 3, as shown best in Fig. 3 of the drawings. Secured to the opposite end of the latch member operating lever 13 from the latch member 12 is a pair of end to end connected coil springs 13d. One of these springs is secured to the latch member operating lever 13 and the other spring is secured to the inwardly extending portion 14a of the reciprocating member 14b of the coin receiving mechanism 14, as shown best in Fig. 3 of the drawings, it being noted that the springs 13d provide yieldable connecting operating means for the latch member operating lever 13 when the inwardly extending portion 14a of the coin receiving mechanism 14 assumes the dash line position C, as shown in Fig. 3 of the drawings. The member 14b of the coin receiving mechanism 14 is modified and provided with a cutaway portion 14c, which cutaway portion 14c is arranged to engage the pin 8b of the operating lever 8, as shown by dash lines in Fig. 3 of the drawings. The principal parts and portions of the coin receiving mechanism are conventional; however, the portion 14a of the member 14b is arranged in connected relation with a spring 14d, which spring 14d tends to hold the member 14b in the solid line position, as shown in Fig. 3 of the drawings. It will be here noted that the general timing mechanism and the general coin receiving mechanism disclosed herein are conventional and no part of my present invention.

The operation of my coin operated typewriter control apparatus is substantially as follows: The conventional typewriter, as illustrated by dash lines in Fig. 1 of the drawings, is provided with a conventional typewriter key control bar A, which is arranged to engage the lower side edges of the typewriter key shank portions. This typewriter key control bar member A, when in the position as shown in Fig. 1 of the drawings engages all of the typewriter key shank portions. The typewriter key retaining lever 11 is provided with a notch portion 11f in its upwardly extend-

ing end, which notch portion 11f is arranged to engage the lower side of the typewriter key control bar member A, as shown best in Fig. 1 of the drawings, whereby this typewriter key control bar member A is secured in rigid position so that none of the typewriter keys may be pressed downwardly in the normal operating manner. The slotted portion 14d in the top member 14a of the cabinet 1 provides sufficient room for pivotal movement of the typewriter key retaining lever 11, as shown best in Fig. 1 of the drawings. Figure 1 of the drawings illustrates the typewriting key retaining lever 11 in disengaged relation with the typewriter key control bar A which position permits normal operation of the typewriter.

Assuming that the typewriter key retaining lever 11 is in the dash line position B and that a person wishes to use the typewriter, said person must insert a coin into the coin receiving mechanism 14 and press the member 14b into the dash line position C as shown best in Fig. 3 of the drawings. When this member 14b passes inwardly to the dash line position C, the cutaway portion 14c thereof engages the upwardly extending pin 8b of the operating lever 8 forcing said operating lever 8 into the dash line position D carrying with it the trip lever 10. The ratchet pawl members 6 and 7 engage the ratchet wheel 5 when the operating lever is in the dash line position D and the clockworks in connection with the main spring casing 4b start to operate in the conventional manner under the force exerted by the tension spring 8a in connection therewith. When the operating lever 8 is forced into the dash line position D by the cutaway portion 14c of the member 14b, the trip lever 10 is pressed into the solid line position, as shown best in Fig. 3 of the drawings and the notch portion 9d of the latch arm 9 slips over the upwardly extending pin 10a of the trip lever 10 and latches the trip lever 10 in the solid line position, as shown best in Fig. 3 of the drawings. When the portion 14b of the coin receiving device is pressed inwardly to the dash line position C, the latch member 12 is shifted to the dash line position J by means of the lever 13 and springs 13d and is then released to the dash line position H as the portion 14b returns to the solid line position permitting the typewriter key retaining lever 11 to shift and release the key control bar A.

The timing mechanism 4 operates slowly in the conventional manner and permits the operating lever 8 in connection with the ratchet wheel 5 to pivot slowly toward the latch arm 9, as indicated by the arrow in Fig. 3 of the drawings. When the pin 8b of the operating lever 8 engages the curved portion of the latch arm 9, the latch arm 9 is shifted into the dash line position E releasing the pin 10a from the notch 9d in the latch arm 9 permitting the trip lever 10 to snap into the dash line position F. When the trip lever 10 snaps into the dash line position F, the end portion 10d thereof presses the lower end 11g of the typewriter key retaining lever 11 inwardly between the arm portions 12e and 12d and the hook portion 12f of the arm 12d engages the edge portion 11e of the typewriter key retaining lever 11 holding this typewriter key retaining lever 11 into dash line position B. As hereinbefore described, when this lever 11 is in the dash line position B, the notch portion 11f engages the lower side of the typewriter key control bar member A rendering the typewriter inoperative until another coin is inserted in the coin receiving

mechanism 14. It will be here noted that when a coin is inserted in the coin receiving mechanism 14 and the member 14b is pressed inwardly into the dash line position C, the coil springs 13d interconnecting the portion 14a and the end of the latch member operating lever 13 tend to shift the latch member operating lever 13 into the dash line position G whereby the edge portion 11e of the typewriter key retaining lever 11 is engaged by the hook portion 12g of the latch member 12 preventing the tension spring 14c from releasing the typewriter key retaining lever 11 from the typewriter key control bar member A before the coin is within the cabinet 1. The trip lever 10 at its portion 10d engages the edge portion 11e of the typewriter key retaining lever 11 and holds the lower end portion 11g thereof inwardly between the arm portion 12e and 12d of the latch member 12 while the latch member 12 is shifting from the dash line position H to the dash line position J. This latch member 12 assumes the dash line position J before the end portion 8c of the operating lever 8 engages said trip lever 10 and disengages said trip lever 10 from the edge 11e of the typewriter key retaining lever 11. The particular structure as disclosed is arranged to limit the use of the typewriter in connection therewith to substantially thirty minute periods; however, the stroke of the operating lever 8 in its relation with the latch arm 9, may be increased or decreased to provide different length periods of time. The ratchet pawls 6 and 7 are arranged to alternate in their engaged relation with the teeth portions 8d so that one of the pawls 6 and 7 engages a notch portion while the other engages one of the teeth portions providing an engaged relation of the pawls 6 and 7 equivalent to one-half the spaced relation of the teeth 8d providing fine adjustment of time periods in relation with the operating lever 8.

Though I have shown and described a particular construction, combination and arrangement of parts and portions, I do not wish to be limited to this particular construction, combination and arrangement, but desire to include in the scope of my invention the construction, combination and arrangement substantially as set forth in the appended claims.

Having thus described my invention, what I claim as new and desire to secure by Letters Patent is:

1. In a coin operated typewriter control apparatus of the class described, the combination with a typewriter having a key control member 55 near its lower side, of a typewriter table on which said typewriter is secured, an enclosed casing positioned under said table top directly under said typewriter, a typewriter key retaining lever pivotally mounted on said enclosed casing and extended through said table top and arranged to engage said typewriter key control bar member, a coin controlled mechanism in operative relation with the lower end of said lever for controlling the shifting of said lever into and out of engagement with said typewriter key control bar member, said coin operated typewriter control apparatus including tension spring means mounted in said enclosed casing in connection with said lever tending to hold said lever out of engagement with said typewriter key control bar member, and reciprocally mounted gear and ratchet means in engagement with the lower end of said lever member arranged to shift it in opposed relation with said spring.

2. In a coin operated typewriter control apparatus of the class described, the combination with a typewriter having a key control member near its lower side, of a typewriter table on which said typewriter is secured, an enclosed casing positioned under said table top directly under said typewriter, a typewriter key retaining lever pivotally mounted on said enclosed casing and extended through said table top and arranged to engage said typewriter key control bar member, a coin controlled mechanism in operative relation with the lower end of said lever for controlling the shifting of said lever into and out of engagement with said typewriter key control bar

member, said coin operated typewriter control apparatus including tension spring means mounted in said enclosed casing in connection with said lever tending to hold said lever out of engagement with said typewriter key control bar member, and reciprocally mounted gear and ratchet means in engagement with the lower end of said lever member arranged to shift it in opposed relation with said spring, said enclosed casing under said table top being hinged to said table top and means for locking the same in closed interlocked position.

JESSE B. GRAHAM.
